Patented Apr. 6, 1920.

Inventor

Daniel Hoyt

By J. Smith Attorney

UNITED STATES PATENT OFFICE.

DANIEL HOYT, OF EAST ORANGE, NEW JERSEY, ASSIGNOR TO THE NATIONAL LOCK WASHER COMPANY, OF NEWARK, NEW JERSEY, A CORPORATION OF NEW JERSEY.

CURTAIN-FIXTURE.

1,335,968.

Specification of Letters Patent.

Patented Apr. 6, 1920.

Application filed June 30, 1919. Serial No. 307,723.

To all whom it may concern:

Be it known that I, DANIEL HOYT, a citizen of the United States, residing at East Orange, in the county of Essex and State of New Jersey, have invented certain new and useful Improvements in Curtain-Fixtures; and I do declare the following to be a full, clear, and exact description of the invention, such as will enable others skilled in the art 10 to which it appertains to make and use the same.

This invention relates to curtain fixtures, in which a spring tensioned roll is employed at the top, and constantly tends to wind the 15 curtain up, the bottom of the curtain being equipped with the curtain fixtures which operate in grooves at the sides of the window frame.

This curtain fixture is designed as an improvement on my patented curtain fixture set forth in my U. S. Letters Patent No. 676,557, issued June 18, 1901, wherein a locking cam is employed which operates directly against the floor of the grooves in the 20 window casing and rigidly locks the curtain against upward movement, also preventing the movement of the rollers which track against the grooves. In my present improvement I employ a locking cam which 25 operates directly on the roller to prevent it from revolving in one direction and to thereby hold the curtain against the tension of the main curtain roll, the rollers being 30 free to revolve in the opposite direction 35 when the curtain is pulled down.

In the accompanying drawing—

Figure 1 is a horizontal broken sectional view of my improved curtain fixture, and

Fig. 2 is an end view.

Referring to the drawing, 1 represents a metallic tube made as long as the width of the curtain, 2 is a head preferably made of sheet metal and formed with a channel way 3, 4 is the shank to one end of which the head 2 is secured, said shank being of a diameter to slide freely within the end of the tube. A rod 5 is secured to the inner end of the shank 4 and extends within the tube 1 to near the center thereof, the inner 45 end being screw threaded as shown at 6.

On the rod 5 is placed a coil spring 7 one end of which bears against the shank 4 the other end abutting against a collar 8 secured on the rod 5.

In the channel way 3 of the head 2 is

pivoted a roller 9 which may be smooth or corrugated, such roller extending outwardly beyond the head 2. At the ends of the head 2 are pivoted antifriction rollers 10, 11, which extend slightly beyond the head 2 but 60 not so far in this respect as the main roller 9.

These rollers 10, 11, are merely anti-friction rollers serving to steady the movements of the head and possibly to render it more stable, but they are not necessary and may 65 be eliminated, if desired.

Above the roller 9 is pivoted a locking cam 12 and a similar cam 13 is pivoted below said roller. The upper cam 12 is so pivoted that its gravity will cause the cam to contact the circumference of the roller 9, while the similar cam below said roller will by gravity drop away from the latter as shown and will, therefore, lie dormant, but should the head be reversed in installing the curtain the lower cam then becomes the upper cam and will contact the roller while the upper cam will become the lower cam and will drop away from such roller. This arrangement of cams is very convenient since 70 it makes no difference which end of the head is in the uppermost position when the fixture is installed.

In assembling the fixture the threaded end of the rod 5 is screwed into the shank of a 75 suitable finger piece 14 which is usual in devices of this description.

When the fixture is attached to a curtain and properly adjusted in the window frame the roller 9 is driven by the spring 7 firmly 90 against the floor of the groove in the window casing, and the uppermost locking cam will rest on top of this roller 9, as shown in the drawings.

When the spring tensioned roll at the top 95 of the curtain exerts its force to roll the curtain up, the natural tendency would be for the roller 9 to revolve outwardly but the locking cam instantly wedges against the roller to prevent it from turning in that direction, and such roller then becomes a friction member which holds the curtain against the action of the main roll at the top thereof.

To operate the curtain, the proper method is to compress the finger pieces 14, which 100 withdraws the rollers from contact with the grooves in the casing, and the fixture is then free to move either up or down, but many passengers, through carelessness or ignorance, grasp the curtain at the bottom 110

and push it up or pull it down, and they often bend the tube or leave the curtain in an unsightly tilted position or pull the fixture out of the grooves.

5 With my improved curtain fixture, if the curtain is pushed up by grasping the bottom, the spring 7 will yield, and if one side of the curtain is pulled down the opposite side will roll down on the roller making this 10 practically a self righting curtain fixture.

I claim:

1. A device of the character described, comprising a tube, a spring pressed shank 15 slideable in the end of the tube, a channel head secured to said shank, a roller pivoted within said head and extending beyond the same, and a locking cam pivoted in said head above the roller said cam preventing the turning of said roller in one direction but 20 allowing it free movement in the opposite direction.

2. A curtain fixture head, comprising a roller pivoted therein and extending beyond the same, and a locking cam pivoted in the 25 head above the roller and operating to prevent movement of the latter in one direction but allowing free movement in the opposite direction.

3. A reversible curtain fixture head, comprising a channeled head, a roller pivoted 30 therein and extending therebeyond, and

locking cams pivoted within said head above and below said roller and adapted to engage the latter and lock it as against movement in one direction the lowermost cam always falling out of engagement with the roller and lying dormant.

4. A device of the character described, comprising a tube, a spring pressed head at the end of the tube, said head extending 40 above and below the tube, friction rollers pivoted within the head at the ends thereof, a centrally disposed roller pivoted within the head and extending therebeyond and adapted to contact the floor of the groove in 45 the window casing, the friction rollers being out of contact with said groove when the fixture is in a horizontal position but adapted to bear when the fixture is tilted, and gravity cams pivoted within said head 50 above and below said central roller and adapted to contact therewith to prevent revolution of said roller in one direction, the lowermost cam always dropping by gravity out of contact with the central roller.

In testimony whereof I affix my signature in presence of two witnesses.

DANIEL HOYT.
